UNITED STATES PATENT OFFICE.

JOSEPH L. MATTHEWS, OF HIGHLAND PARK, NEW JERSEY, ASSIGNOR TO INTERNATIONAL MOTOR COMPANY, OF NEW YORK, N. Y., A CORPORATION OF DELAWARE.

SAND-BLAST NOZZLE.

1,393,562.

Specification of Letters Patent.

Patented Oct. 11, 1921.

Application filed October 8, 1920. Serial No. 415,495.

To all whom it may concern:

Be it known that I, JOSEPH L. MATTHEWS, a citizen of the United States, residing at Highland Park, in the State of New Jersey, have invented certain new and useful Improvements in Sand-Blast Nozzles, of which the following is a specification, reference being had to the accompanying drawing, forming a part hereof.

10 This invention relates to sand blast nozzles and is designed primarily with reference to nozzles used on the table type of sand blast machine for sand blasting hardened parts. As the description proceeds, however, it will be evident that the invention can be adapted to nozzles of other types used in sand blasting operations in different arts.

The present problem has arisen in commercial practice by reason of the short life 20 and relatively high cost of the chilled iron nozzle in use. It has been found, in practice, that the average life of such a nozzle is only about thirty minutes after which its bore becomes so abraded as to require the 25 nozzle to be discarded. These nozzles are relatively expensive even when purchased in quantity and the number used results in the discarding of so many nozzles that the expense becomes very burdensome. In accordance with the present invention it is proposed to provide a relatively wear resisting material in the nozzle to direct the stream of sand. This material can be provided in the nozzle as a lining for the bore, as a tip, 30 or the nozzle body can be formed of it. In the preferred construction, however, a metal body is formed and either a liner or a tip of a ceramic or a composition thereof is so mounted within the metal body as to direct 35 the stream of sand and protect the metal from the abrasive action thereof. The commercial product known as stellite or porcelain has been found suitable for the purpose. Reference is now to be had to the accompanying 40 drawing for a detailed description of illustrative embodiments of the invention, in which—

Figure 1 is a view in section of a metal nozzle formed for the reception of a lining 45 of wear resisting material.

Fig. 2 is a view in section of the nozzle shown in Fig. 1 and showing such wear resisting liner in place.

Fig. 3 is a view in section of a nozzle having a removable liner.

As indicated hereinbefore, it is preferred 55 to form the nozzle of metal, as heretofore, but to provide a lining for its bore, or a portion thereof, which lining shall be of such material as to resist effectively the 60 abrading action of the sand. In some instances, it may be found desirable to pour 65 the liner material directly into the bore and let it set permanently therein, the bore of the nozzle being provided with recesses or 70 the like so that the liner material after it sets will be anchored permanently in place. In other embodiments the nozzle may be provided with a tip of wear resisting material which tip may extend for a part only 75 of the length of the bore or may extend throughout its length and will be removably secured to the nozzle for ready replacement.

In the embodiment illustrated in Figs. 1 and 2 the nozzle *a* is formed of metal and is 75 cast with transverse corrugations *a'* in its bore *a²*, these corrugations being shown as extending circumferentially of the bore. It is evident that they may be of some other form and serve the intended purpose. Into 80 the bore *a²* of the nozzle is poured some ceramic or a composition thereof, such as porcelain or stellite, this material being indicated at *b* in Fig. 2. It will be molded as a liner directly into the corrugations *a'* and is 85 shown as extending throughout the length of the nozzle *a* and as providing the bore therefor. The sand will have little or no abrading action on such a liner so that the useful life of the nozzle will be materially 90 lengthened. Further, it is obvious that the liner can be replaced when broken or so worn as to become unsuitable.

In the embodiment illustrated in Fig. 3 there is provided a molded removable liner *B* 95 which can be slipped into the bore of the nozzle *A* and retained in place by any suitable mechanical retaining devices. For instance, one end of the nozzle *A* can be recessed and threaded, as indicated at *A'* to receive a 100 threaded flange *B'* on the end of the liner *B*. This permits the liner to be readily secured removably in place. It will be evident to the skilled mechanic that other positive mechanical retaining devices might be employed for holding the liner *B* in place.

Further, it is apparent that while the liner is shown as extending throughout the length of the bore of the nozzle A, this liner might be molded as a tip and be inserted at either 5 end of the nozzle and extend for only a portion of the length of the bore while receiving the direct action of the sand at its most abrading section.

A further embodiment of the invention, 10 unnecessary to illustrate, will be found in the molding of an integral nozzle of a ceramic or a composition thereof having a bore of wear resisting material, but such a

unit for reasons understood in the art would not be the most practical or serviceable construction. 15

What I claim is:

1. In a sand blast nozzle, a lining of ceramic material.
2. In a sand blast nozzle having a body of 20 metal, a liner for the bore thereof formed of ceramic material and means to secure said liner in place.

This specification signed this 4th day of October, A. D. 1920.

JOSEPH L. MATTHEWS.
